THREAD MANUFACTURING REEL HAVING LIQUID APPLYING AND LIQUID REMOVING MEANS

Harry A. Kuljian, Merion, Pa.

Application July 13, 1953, Serial No. 367,664

8 Claims. (Cl. 68—205)

My invention relates to a thread manufacturing or treating apparatus of the general type set forth in my prior Patents Nos. 2,543,031 of February 27, 1951, and 2,616,155 of November 4, 1952.

One object of the invention is to produce an improved apparatus of the type disclosed in said patents.

In the type of apparatus referred to, various treating liquids are used in processing the thread. In order to make sure that the various liquids needed are present in sufficient quantities, and because it is difficult, if not impossible, to gauge the liquid requirements exactly, it is the practice to supply the various liquids in relatively excessive amount. But, because at least some of the liquids used are expensive, because the presence of liquids in excessive quantities will result in intermingling of the various liquids delivered to adjacent zones on the roll with obviously undesirable consequences, and because the presence of an excessive quantity of one reagent or another may, of itself, produce undesired results, it is desirable to remove excess liquids so as to regulate the quantities of the various liquids which are allowed to remain on the filament or on the rolls during movement of the filament through successive zones along such rolls. It is also desirable that the excess liquids be removed, as far as possible, in a segregated manner so as to facilitate reclamation and reconcentration of the various liquids.

To this end, I have heretofore devised the liquid scraping and segregating apparatus shown in my prior Patent No. 2,634,449, in which the liquid scrapers are urged against the roll by means of springs, and are satisfactory for most uses. However, I have discovered that if the scraper is urged against the roll by something which is more sensitive, more yielding, and more readily adjustable, better results can be obtained.

It is therefore a further, and more specific, object of the invention to produce an improved liquid scraping and segregating means of the type disclosed in said Patent No. 2,634,449.

According to my invention, I use a pneumatic pressure member for urging the scraper against the roll and I mount the pneumatic pressure applying member in such a manner as to enable it to apply constant following pressure over the entire surface of the scraper.

The full nature of the invention will be understood from the following specification and the accompanying drawings, in which:

Fig. 1 is a diagrammatic side elevational view of a thread manufacturing, or treating, apparatus embodying my invention, only enough of the apparatus, proper, being shown to show the relation of the invention to the other parts of the apparatus.

Fig. 2 is a section on line 2—2 on Fig. 1, again only so much of the structure being shown as is necessary to locate the invention relative to the other parts.

Fig. 3 is a view, partly in elevation and partly in section, showing one way of mounting the pneumatic pressure applying member.

2

Fig. 4 is an enlarged sectional view taken on line 4—4 on Fig. 3 and showing the pneumatic pressure applying member in its inflated condition.

Fig. 5 is similar to Fig. 4 but showing the pneumatic pressure applying member in its deflated condition.

Fig. 6 is an enlarged, fragmentary view, partly in section and partly in elevation, showing details of construction of the pneumatic pressure applying member.

Fig. 7 is similar to Fig. 3 but showing a different way of mounting the pneumatic pressure applying member.

Fig. 8 is an enlarged sectional view taken on line 8—8 on Fig. 7 and showing the pneumatic pressure applying member in its inflated condition.

Fig. 9 is similar to Fig. 8 but showing the pneumatic pressure applying member in its deflated condition.

Fig. 10 is an elevational view of the concave face of the scraper which contacts the roll.

Fig. 11 is a fragmentary sectional view showing the use of one pneumatic pressure applying member to two adjacent rolls.

The apparatus shown in Fig. 1 includes a number of rolls 10, 11, 12, 13, 14, 15, 16 and 17 the opposite ends of which are journaled in end plates 18 and 20 which are mounted on a center post 22. The center post 22 is carried by a suitable frame not shown. The apparatus further includes a motor M, which, by means of gears, not shown, rotates rolls 10 to 17 on their respective, individual axes. The end plate 18 is secured by a nut or the like 24 and upon loosening of the nut, the end plate 18, and the ends of the rolls journaled therein, may be rotated slightly relative to end plate 20 to skew the axes of the rolls 10 to 17 and thus form a thread storing and advancing device. The structure and operation of the thread storing and advancing reel form no part of the present invention, and they are therefore not shown nor described. For a more complete understanding of the structure and operation of the thread storing and advancing device, reference may be had to my above mentioned and other patents. For the purpose of this invention it is enough to state that, when the thread 26

is wound about the receiving end of the reel so as to encompass all of the rolls, it will form a helix the convolutions of which will move, longitudinally of the reel, from the receiving to the discharge end of the reel. In Fig. 1, the thread 26 is shown as a nascent filament which has

just been formed by extruding viscose through a spinnerette 28 into a coagulating bath 30. This is by way of illustration only as the source of the thread is immaterial. As the thread moves over successive portions or

50 zones of the roll 11 (or roll 10), various treating liquids are poured over the thread from spaced nozzles N. These liquids are conventional and have been in common use in the industry for about fifty years and therefore need not be described, chemically or functionally, beyond saying that sulphuric acid will be applied in one zone, sodium

55 hydroxide in another zone, water in another zone, soap in another zone, sodium carbonate in another zone etc. As the thread traverses the portion of the roll to the left of the endmost nozzle, as shown in Fig. 1, the filament is dried by means of a heater, which forms no part of the present invention and which may be of the type shown in my prior Patent No. 2,613,451.

In order to remove excess liquids from rolls 10 and 11 (and from other rolls, if desired) I provide the scraper shown in Fig. 10 and I mount the pressure applying member as shown in Fig. 3 or in Fig. 7. In either case, the scraper is urged against the roll by means of the pneumatic pressure applying member of Fig. 6. When a fine thread is to be produced for use in textile fabrics, two scrapers A and B are used, side by side, as shown in Fig. 1. This is due to the fact that this type of thread requires better and longer regeneration and fin-

ishing. On the other hand when a coarse thread such as tire cord is to be made, the regeneration treatment is shorter and only one wiper A is used at the receiving end of the reel. In either case, the scraper includes an arcuate shell 31 the concave face of which is provided with wiping or scraping elements 32 which form a series of connected upright and inverted V formations, as best shown in Fig. 10. At the apex of each upright V formation is a drain hole 33, and below each shell is a trough 34 which is preferably provided with partitions 36 to form separate compartments for receiving the different liquids drained through holes 33. The open, or upper ends of the V formations, in single units or in multiples, are coextensive with the zones on the roll to which the different liquids are delivered. For example, the space between points C and D will correspond to the zone to which acid is delivered, and the space between points D and E will correspond to the zone to which soap is delivered and so on. Obviously, if a treating zone is particularly long, it may correspond to the distance between points C and E instead of to the space between points C and D only and so on. It will be noted that the inclined scraping elements 32, being continuous, scrape over the entire surface of a roll to which they are applied. Also, the scrapers which terminate at C and D, for example, will direct the liquid scraped thereby from the corresponding zone on the roll 11 to the endmost drain hole at the left end of Fig. 10 and so on.

In order to apply following pressure against the scraper and in order that such pressure be constant and uniform throughout I have devised the pneumatic pressure applying member 38 which is best shown in Fig. 6. The member 38 is preferably a rubber tube which is coextensive with shell 31 so as to have yielding contact with the entire convex surface of the shell. The member 38 may be filled with air under the desired pressure and sealed, or it may be connected, by pipe 40 to a source of compressed air, not shown. If desired, a valve 42 which operates to maintain the pressure at a constant value, or which can automatically regulate the pressure within member 38 may be used. When two scrapers A and B are used, one member 38 can be used which is coextensive with both of the shells or a separate pressure applying member 38 can be used for each separate scraper. The member 38 is carried in a housing 46 and its diameter is such that, when it is deflated as in Figs. 5 and 9, it will not project beyond the inner edges 48 of the housing, and that, when it is inflated, it will bear against the convex side of shell, or shells, 31 to press the scrapers 32 against the roll 10 or 11. See Figs. 4 and 5 and Figs. 8 and 9.

Since air pressure within member 38 is equal in all directions it follows that it will exert more uniform pressure against the scrapers than is exerted by a spring such as that shown in my said prior Patent No. 2,634,449.

It is of course possible to use a cushion member which is solid or hollow and the resiliency of which is depended on to exert the desired pressure without the use of compressed air. For example, a rubber tube, or a solid rubber rod, the diameter of which is as large as, or slightly larger than, the diameter of member 38 in its inflated condition will perform satisfactorily, but it will not be capable of regulation.

The housing 46 may be supported in position in any suitable manner. As shown in Fig. 3 the housing is supported by a plate 50 which is carried at one end thereof, by the bearing of shaft 52 of the roll. If this support is not enough, the other end of the housing can also be supported by a plate, or bracket, not shown, which can be carried by end plate 22, by center post 18 or by any other fixed frame. The exact arrangement does not matter as the point is that, in this embodiment, the housing 46 which carries pressure member 38 is not

carried by the shaft of the roll to which the scraper is applied but by an independent support.

In the structure of Figs. 7 to 10, the housing 46 is carried by brackets 54 which are carried by the opposite ends of the shaft 52 of the corresponding roll so that each roll and its scraper assembly form a unitary structure. In this arrangement, the scraper, being carried by the roll, it will adapt itself more readily and more accurately to movement or change of position of the roll than it can when the housing 46 is carried by a support which is independent of the roll as in Fig. 3.

In all cases, each of the shells 31 is provided with one or more lugs 56, which, when the reel is assembled, rest upon the upper walls of housings 46 as clearly shown in the drawings. The engagement of lugs 56 with the tops of the housings 46 serves to prevent rotation of the shells 31 and they also serve as handles with which the shells 31 may be removed. It will also be noted that the shells 31 are not fastened to anything in any way so that they are free to pivot in all directions so to adjust themselves perfectly to the rolls to which they are applied.

It will thus be seen that I have produced an improved construction in which the scrapers are not in any way fastened so that they are wholly free to have a floating contact with the rolls whereby the scrapers can constantly, readily and accurately adjust their contact with the rolls, and that the scrapers are urged against the rolls with a yielding pressure which is uniform throughout and which can adjust itself in a localized manner. In other words, if there is more resistance at one point and less resistance at another point, the corresponding portions of the resilient member 38 will yield or will follow as the case may be.

In Fig. 11 I show a modification in which the shells 31 are placed back to back with their concave faces abutting adjacent rolls and I use a single pneumatic pressure applying member 56 located between and adapted to bear against the convex sides of the shells 31. The single pneumatic pressure applying member may be mounted in any suitable manner. As shown in Fig. 11, I provide a housing 58 provided with side openings through which the pressure member bulges so as to press against the shells 31.

It will be noted that, when the tube 38 is collapsed, as in Figs. 5 and 9, there is ample play between the wiper and the roll and between the wiper shell and the housing 46 whereby the entire wiper assembly can be lifted out, or inserted in position, easily and without removing any of the parts. In other words, the wiper assembly is attached to nothing and is supported in position only by lugs 56 resting on the top wall of housing 46 and the only engagement of the wiper with the roll is that caused by the pressure exerted by pipe 38 when it is inflated.

What I claim is:

1. A thread manufacturing apparatus including at least one rotary roll over which the thread is adapted to pass, means for applying at least one liquid to roll, a wiper engaging a portion of said roll for scraping off liquid from a portion of said roll, and an air cushion mounted in pressure contact with said wiper and serving yieldably to urge said wiper against said roll, said cushion being formed of resilient elastic material.

2. The structure recited in claim 1 in which said wiper is elongated and said air cushion is in the form of an elongated cylindrical member extending longitudinally of the wiper.

3. A thread manufacturing apparatus including a supporting frame, at least one rotary roll over which the thread is adapted to pass, a shaft for said roll carried by said frame, means for applying at least one liquid to said roll, and means for scraping off liquid from a portion of said roll, said means including an elongated wiper having a concave inner face adapted to contact the roll, an elongated support adjacent the outer side of said

wiper, an elongated, resilient, elastic, hollow member carried by said support, means for admitting compressed air into, and retaining it in, said hollow member, to expand said hollow member into contact with the outer side of said wiper to press the latter with following yielding pressure against said roll.

4. The structure recited in claim 3 in which said support is carried by the ends of the shaft of the roll.

5. The structure recited in claim 3 in which said support is carried by said frame.

6. The structure recited in claim 3 in which said wiper is loosely placed between said roll and said support and a lug extending laterally from the outer side of said wiper and resting on said support, said lug being the sole means for limiting the downward movement of said wiper and for preventing rotation thereof with the rotation of the roll.

7. The structure recited in claim 3 in which said support is generally U-shaped in transverse section with the open side of the U facing the outer side of the wiper and in which the diameter of the hollow member, when deflated, is smaller than the length of the limbs of the U whereby, in the absence of predetermined air pressure therein said hollow member will not contact the wiper.

8. The combination with a thread manufacturing apparatus of the type which includes a number of rolls arranged to form a thread storing and advancing reel, means for applying a liquid to the thread as it passes over at least one of said rolls, and an elongated scraper engaging an elongated portion of the surface of said one roll for removing some of said liquid from said roll, of means for applying following pressure to said scraper to urge it against said roll, said means including an elongated, resilient, elastic hollow member, means for supplying fluid pressure to the interior of said member, and means for mounting said hollow member adjacent said wiper in such a manner that, when said hollow member is inflated it will bear against the corresponding portion of said scraper and so that, when said hollow member is deflated, it will be out of contact with said scraper.
